United States Patent Office.

LEVI MOORE, OF BARABOO, WISCONSIN.

Letters Patent No. 80,652, dated August 4, 1868.

IMPROVED CLAY-MILL.

The Schedule referred to in these Letters Patent and making part of the same.

TO ALL WHOM IT MAY CONCERN:

Be it known that I, LEVI MOORE, of Baraboo, in the county of Sauk, and State of Wisconsin, have invented a new and improved Mill for Grinding Clay; and I do hereby declare that the following is a full, clear, and exact description thereof, which will enable others skilled in the art to make and use the same, reference being had to the accompanying drawings, forming part of this specification.

Figure 1 is a vertical cross-section of my invention through the line *x x*, fig. 2.

Figure 2 is a horizontal section, taken through the line *y y*, fig. 1.

Similar letters of reference indicate corresponding parts.

The object of this invention is to provide a mill for reducing clay to a pulverulent and plastic state, suitable for building-brick or pottery.

It consists of the form and arrangement of the grinding-devices herein set forth.

The grinding-mechanism is located within a frame, A, forming part of the box, containing several floors, from which the clay passes in the several stages of the operation.

I is a shaft, bearing the rotating grinding-disk and grinding-arms. This shaft has its upper bearing in the cross-beam B, and bears a cog-wheel, C, by means of which the power is transmitted to it.

The lower bearing is on the gudgeon *m*, affixed to the bottom cross-beam J, one end of which rests in a recess in the frame of the machine, and with sufficient looseness to permit the cross-beam the slight vibration for adjusting the mill to grind fine or coarse, which is done by means of a set-screw, *n*, as will be shown.

The boss D', forming part of the toothed grinding-plate *a a*, furnishes another bearing for the shaft, and the boss *l*, of the bottom grinding-plate P P, furnishes also another bearing for the same shaft.

The grinding-plate *a a* is a single plate of cast iron, formed with wedge-shaped projections *d d d*, to its under side.

The ends of this plate rest in recesses in the side of the box of the machine, which are provided with springs *p p*, which actuate the plate upward against the points of the set-screws *o o*, by which means the said plate is controlled and adjusted to grind fine or coarse, as will be shown.

L L is the grinding-disk, and is of cast iron. It is formed with wedge-shaped projections *e e e* on its upper and under side, which projections are arranged to pass between the similar corresponding projections *d d d*, &c., and *fff*, on the grinding-plates *a a* and M M respectively.

The clay is ground and rendered suitably plastic by the friction it receives from the projections of the several plates passing in close proximity to each other.

The plate M is of cast iron, and consists of four radial arms, resting on and affixed to the floor D. The projections *fff*, &c., of the plate M, are similar to those of the disk L.

A circular opening, O, in the floor D permits the clay to pass through to the lower grinding-plate G G P P. The plate G G has four radial arms, extending from a hub, *k*, and projections *hh h*, &c., similar to those above described.

The plate P P is affixed to the bottom, H, and provided with projections *iii*, &c., similar to those above described. This latter plate is also of cast iron, and in the form of four radial arms.

E E are doors, opening into the cavity of the box on the plane of the floor D. Q Q are similar doors, opening into the cavity of the box on the plane of the bottom, H, both upper and lower doors being provided with suitable knobs to open them.

The doors E are swung open on hinges, but the doors Q Q are lifted vertically into recesses, which recesses are provided with guide-strips *r r* to retain the doors in place.

The clay is thrown into the hopper K, and upon the revolving disk L L, which, in conjunction with grinding-plate *a a*, grinds it up, at the same time working it from the centre outward to the periphery of the disk, over which it falls through space *u* between the disk and the box, falling upon the floor D, where it is further ground by the disk and lower plate M M. At this point, the lumps, sticks, and pebbles are worked outward and

discharged through the doors E E, while the more plastic and fluent clay is conducted, by the chutes N, to the central opening O in the floor D, and thence to the grinding-plates G G P P, when its is more perfectly comminuted.

The clay then passes out through the doors Q Q into the moulds or other receptacle, being suitably prepared for the manufacture of brick or pottery-ware.

The projections of the grinding-plates and the disk are alike, all being similar to those shown at *fff*, &c., in fig. 2.

The projections of each plate, as *i* and *h*, are reversed, that is to say, the points are in opposite directions, and this and these surfaces are curved slightly, which form conduces to the squeezing of the clay between them.

When the cross-beam J is raised, by means of the set-screw *n*, the grinding-plate G G and disk are removed from their fixed plates, and the clay is thereby less finely comminuted, but, when the said cross-beam is lowered, the revolving parts are brought down into closer relation with their respective plates, and the clay is ground more finely.

The plate *a a* is adjusted by the set-screws *o o* in accordance with the raised or lowered posts of the disk.

The doors E E are closed when the mill is in operation, being only opened from time to time to extract the sticks and other hard bodies that are worked out to the periphery of the disk.

The more fluent and plastic portion of the clay passes down the chutes N in advance of that which is less fluent, which latter follows in turn as it becomes equally fluent, thus leaving the stones and sticks at the edge, and conveniently accessible for being extracted through the doors.

The disk may be substituted by a grinding-plate of two or four arms, having projections similar to those of the disk when the clay is ground for brick, as it is not requisite that it should be so fine as for pottery-ware.

I claim as new, and desire to secure by Letters Patent—

The disk L, with its projections, in combination with the grinding-plates *a* and N, the floor D, having chutes and opening O, the horizontal grinding-plates G P, having wedge-shaped projections, the shaft I, floor H, and doors Q Q, all substantially as and for the purpose shown and described.

LEVI MOORE.
